UNITED STATES PATENT OFFICE.

ROBERT L. DENNISON, OF NEW YORK, N. Y.

STEERING PROPELLER FOR SHIPS.

Application filed August 4, 1925. Serial No. 48,156.

This invention relates to steering propellers for ships.

An object of the invention is the provision of a steering propeller construction by means of which a ship may be steered from a state of rest without moving forwardly or backwardly.

A further object is to provide a steering propeller adapted to be driven by a pair of 10 motors having drive shafts extending longitudinally of the ship.

A further object is the provision of an improved bearing or mounting for the motor shafts.

15 In the accompanying drawings I have shown one embodiment of the invention. In this showing,

Figure 1 is a side elevation of the stern of a ship,

20 Figure 2 is a horizontal sectional view substantially on line 2—2 of Figure 1,

Figure 3 is a similar view on line 3—3 of Figure 1,

25 Figure 4 is a side elevation of a thrust bearing employed on the propeller shaft,

Figure 5 is a vertical sectional view through the motor shafts, and their bearings taken on line 5—5 of Figure 2, and,

30 Figure 6 is a vertical sectional view on line 6—6 of Figure 3.

Referring to the drawings, the reference numeral 1 designates generally the hull of a ship having a deck 2. The ship may be provided with the usual rudder 3 mounted 35 on a vertical axis and having a bevel gear 4 adapted to be actuated from a control shaft 5 by means of a bevel gear 6.

The ship may also be provided with suitable propellers 7 driven from a suitable 40 source of power by means of shafts 8 extending through the sides of the ship beneath the water level adjacent the stern of the boat. As shown, these shafts may be mounted in bearing members 9.

45 The steering propeller forming the subject matter of the present invention is adapted to be arranged at the stern of the boat as shown in Figures 2 and 3 of the drawings and in substantially the same horizontal 50 plane as the propellers 7. As shown, the hull of the boat is provided with a transverse section 10 at the stern and a plate 11 extends outwardly therefrom and carries the usual rudder 3. This plate is provided with 55 a circular opening 12 and the steering pro-

peller forming the subject matter of the present invention is arranged within this opening.

In assembling the steering propeller I provide a pair of longitudinally extending 60 bearing members 13 which are tubular in form and are provided with webs 14 of appreciable width on their inner sides and similar webs 15 which are narrower on their outer sides. These bearing members are 65 provided with end flanges 16 shaped to conform to the curvature of the side of the ship and adapted to be secured thereto in any suitable manner as by riveting.

Longitudinally extending motor shafts 17 70 are arranged within the tubular members 13 which form bearings therefor and these shafts are connected to reversible motors 18 arranged within the ship. A gear box 19 is secured to the outer end of each of the bearing members and these gear boxes are adapted to receive pinions 20 which are mounted on the shafts 17 and keyed thereto to revolve therewith. As shown, a bronze bushing 21 may be arranged in the wall of the 75 gear box to receive the shaft 17.

The rear walls of the gear boxes are provided with extensions 22 having openings therein adapted to receive a rudder shaft 23 which extends transversely of the vessel. A 80 bushing 24 may be arranged in each of the bearings formed by the members 22. The steering propeller shaft is adapted to receive a beveled gear or pinion 25 adjacent each end meshing with the bevel gear 20 of 85 the adjacent motor shaft 17.

In the space between the gear boxes I provide a hub 26 mounted on the steering propeller shaft and having a plurality of blades or paddles 27. Adjacent the ends of the 90 steering propeller shaft I provide a thrust bearing consisting of a pair of annular members 28, the inner faces of which are substantially flat and the outer faces of which are convex as shown at 29. The outer face 95 of the inner member 28 is adapted to be received in a concaved portion 30 of the adjacent wall of the gear box. Between these plates I provide a plurality of rollers 31 having their axes arranged radially of the 100 main shaft and mounted on pins 32. The thrust bearings are retained in position by means of nuts 33 arranged on the threaded ends of the steering propeller shaft and suitable covers 34 are arranged over the thrust 105 110

bearings and secured to the outer walls of the gear boxes.

The operation of the device will be apparent from the foregoing description. The steering propeller may be attached to a ship without material modification in the construction of the operating parts of the ship and without interfering with the operation of the propellers 7. The ship is adapted to be steered by revolving the blades 27 of the steering propeller in opposite directions and for this purpose the motors 18 are reversible. By revolving the blades in one direction the ship is caused to steer to the right and by reversing the motors the ship may be caused to turn to the left. An important advantage of the steering propeller is that the vessel may be steered regardless of whether it is under headway whereas in the ordinary rudder construction shown at 3 the vessel must be moving in order that the rudder may function.

By providing the two motors and the two motor shafts 17 together with the thrust bearings arranged at each end of the steering propeller shaft the drive is balanced and the strains on the parts are reduced to a minimum.

It is to be understood that the form of my invention herewith shown and described is to be taken as a preferred example of the same, and that various changes in the shape, size, and arrangement of parts may be resorted to without departing from the spirit of the invention or the scope of the subjoined claims.

I claim:

1. In a device of the character described, a pair of bearing members secured to the exterior of a ship adjacent the stern and extending longitudinally, motor shafts mounted in said bearing members, a steering propeller shaft extending transversely and arranged exteriorly of the ship, a hub mounted on said steering propeller shaft, blades carried by said hub, and gearing connecting

said steering propeller shaft to said motor shafts.

2. In a device of the character described, a pair of bearing members secured to the exterior of a ship adjacent the stern and extending longitudinally, motor shafts mounted in said bearing members, a steering propeller shaft extending transversely and arranged exteriorly of the ship, a hub mounted on said steering propeller shaft, blades carried by said hub, gearing connecting said steering propeller shaft to said motor shafts, and a thrust bearing arranged on each end of said steering propeller shaft. 60

3. A mounting for steering propellers comprising a pair of longitudinally extending members adapted to be secured to the exterior of a ship adjacent the stern, said members being provided with flanges at their forward ends conforming to the curvature of the adjacent portion of the ship and adapted to be secured thereto, said members being further provided with tubular portions for the reception of motor shafts, a gear box 70 secured to the rear end of each of said members, bearings carried by said gear box and adapted to receive a transverse steering propeller shaft, and thrust bearings arranged in said gear boxes. 75

4. In a device of the character described, a pair of longitudinally extending motor shafts, a bearing member for each of said shafts, each of said bearing members comprising a tubular portion having laterally 80 extending webs and provided with a flange at one end adapted to be secured to the side of a ship, a gear box secured to the rear end of each of said members, bearings in said gear boxes, a transversely extending steering propeller shaft mounted in said bearings, gearing connecting said steering propeller shaft to said motor shafts, and a steering propeller mounted on said steering propeller shaft intermediate said gear boxes. 85

In testimony whereof I affix my signature.

ROBERT L. DENNISON. 90
